UNITED STATES PATENT OFFICE.

LULU C. LUX, OF THOMPSON FALLS, MONTANA.

HEN'S NEST.

1,345,205.

Specification of Letters Patent. Patented June 29, 1920.

Application filed September 6, 1918. Serial No. 252,914.

To all whom it may concern:

Be it known that I, LULU C. LUX, a citizen of the United States, residing at Thompson Falls, in the county of Sanders, State of 5 Montana, have invented certain new and useful Improvements in Hens' Nests; and I do hereby declare the following to be a full, clear, and exact description of the invention, such as will enable others skilled 10 in the art to which it appertains to make and use the same.

The primary object of the invention is, the provision of a nest wherein the cover is novel in form so that the same can be 15 readily opened and closed, the cover being formed from a plurality of sections flexibly connected to each other so that on pulling upon the free end section the cover will be brought to closed position and on retrograde 20 movement the cover sections will slide one upon the other for the opening of the nest. The invention consists in the features of construction, combination and arrangement of parts as will be hereinafter fully described, illustrated in the accompanying drawing and pointed out in the claim hereunto appended.

In the accompanying drawing:

Figure 1, is a side elevation of a nest constructed in accordance with the invention, showing the same supported from a wall or other stationary object.

Fig. 2, is a top plan view showing the cover in closed position.

Fig. 3, is a vertical transverse sectional view thereof.

Fig. 4, is a vertical longitudinal sectional view.

Fig. 5, is a detailed perspective view of 40 one of the sections of the cover of the nest.

Similar reference characters indicate corresponding parts throughout the several views in the drawing.

Referring to the drawing in detail, A, 45 designates generally a bracket and B, the socketed keeper adapted to be fixed to a support such as a wall or other standard located interiorly of a hen house or like inclosure. The bracket A, at one end is 50 removably fitted within the socketed keeper B, and at its other end are carried suitable arms 10 for supporting the hen's nest, hereinafter fully described.

The hen's nest comprises a body frame 55 11 having reticulated sides, ends 13 and bottom 14, while the top of the body frame is

open and has mounted thereon a cover hereinafter fully described.

In the sides of the body, near their upper edges are formed longitudinal slots 15 for 60 the cover which comprises a plurality of slats 16 preferably made from sheet metal having their ends 17 slidably engaged in the slots 15, each slat 16 along one edge being formed with an upwardly bent flange 65 18 which is of less length than the slat 16 and lies between the top rails of the body frame 11 of the hen's nest. One of the end slats 16 has its flange 18' fixed to the top rail of the one end 13 of the body frame 70 and the other end slat 16 is free.

Connected to the laterally extended portions of the flange 18' near opposite ends thereof are flexible elements such as chains 19, the latter being connected throughout their 75 lengths at intervals with said several flanges 18 for flexibly connecting the slats 16 together which on the extending of the cover are disposed in slightly overlapped relation to each other and are adapted to nest one 80 over the other in superimposed relation to each other on the opening of the cover. The chains 19 limit the movement of the slats 16 when closing the cover upon the body frame 11 of the hen's nest.

Carried by the free end slat 16 of the cover is a hand knob 20, whereby the cover can be opened and closed manually.

When the cover is closed upon the hen's nest, it prevents the entrance of a second 90 hen to the nest when a setting hen is within the same.

Hinged to the side of the body frame 11 is a hook 21, which is adapted to detachably engage in one of the end extensions of the 95 free end slat 16, for the fastening of the cover in closed position.

Upon the bracket A, and surrounding the same is mounted a cup-like container 22 for receiving coal oil or cedar oil, or any other 100 preparation for preventing lice insects or the like entering the nest when crawling upon the bracket of the wall support of the hen house.

It is thought that the manner of opening 105 and closing the cover to the hen's nest will be obvious, and therefore a more extended explanation has been omitted.

What is claimed is:

A hen's nest, comprising a body open at 110 its top and having longitudinal slots in its sides adjacent to its open top, a plurality

of cover sections whose ends are slidably engaged in the slots and whose bodies are slidable one upon the other to opened or closed position, the sections having at corresponding edges upturned flanges movable between said sides and the flange of one endmost section being secured to one end of the body, chains connecting all the flanges for holding the sections slightly overlapped

when the cover is closed, and means for fastening the other end most section to the body at that time.

In testimony whereof I affix my signature, in the presence of two witnesses.
